UNITED STATES PATENT OFFICE.

EDWARD LORENZEN, OF MARSHALLTOWN, IOWA.

SMOKEHOUSE.

1,413,671.

Specification of Letters Patent. Patented Apr. 25, 1922.

Application filed January 31, 1921. Serial No. 441,405.

To all whom it may concern:

Be it known that I, EDWARD LORENZEN, a subject of Germany, and a resident of Marshalltown, in the county of Marshall and 5 State of Iowa, have invented a certain new and useful Smokehouse, of which the following is a specification.

The object of my invention is to provide a smoke house adapted preferably to be 10 used by farmers who desire to smoke enough meat at one time to last them for several months. The device being of simple, durable and comparatively inexpensive construction.

15 More particularly my invention relates to a smoke house for meat or the like, which is provided with a door and a meat supporting rack rotatably mounted within the smoke house, whereby the meat supporting 20 rack may be moved to position adjacent to the door for either placing meat thereon or removing it therefrom.

Another object is to provide a smoke receiving opening in the container or smoke 25 house which may be connected to a smudge fire box. Also the providing of a vent or discharge opening in the smoke house which may either be open or closed when desired. The smoke receiving opening and vent opening 30 being capable of being used interchangeably so that smoke may be communicated into the smoke house from a fire box placed on either side of the container or smoke house.

35 Still another object is to provide a smudge fire box which is provided with a hinged door and a handle, the handle being adapted to be used as a lock for holding the door in its closed position and when in another position to serve as a handle.

With these and other objects in view, my invention consists in the construction, arrangement and combination of the various parts of my device, whereby the objects contemplated are attained, as hereinafter more 45 fully set forth, pointed out in my claim, and illustrated in the accompanying drawings, in which:

Figure 1 is a side elevation of my smoke 50 house with the fire box connected therewith.

Figure 2 is a central, vertical, sectional view taken through the smoke house or container.

Figure 3 is a horizontal, sectional view 55 taken on the line 3-3 of Figure 2.

Figure 4 is an enlarged, detail, sectional view showing one of the openings communicating with the container; and

Figure 5 is a front elevation of the fire box, one of the positions of the handle being 60 shown in dotted lines.

In the accompanying drawings I have used the reference character A to indicate generally a smoke house or meat container which is substantially cylindrical in form 65 and provided with a cone shaped cover member 10 and a base 11. A reinforcing bank 12 is provided adjacent to the base which may be riveted to the lower edge of the container A and to the base 11 by means 70 of the rivets 13.

The cone shaped cover 10 is also fixed to the container A by means of rivets or the like.

The container A is provided with a door 75 opening 14 and the doors 15 for closing the door opening 14. An ordinary hasp 16 is used for holding the doors 15 in their closed position.

The doors 15 are capable of being opened 80 independently of each other so that access may be had into the container A either at the top or bottom as is desired.

In order to support meat in the container A I have provided a meat supporting rack 85 B which is composed of a center post 17 which has its lower end journaled in a bearing member 18, and its upper member provided with a ball member 19.

A cap member 20 is provided which has 90 an opening substantially the size of the ball member 19 for receiving the ball member 19.

The center post 17 extends up through the peak of the cone shaped cover member 10. The cap member 20 is riveted to the member 10.

It will be seen that the meat supporting rack B is capable of rotation within the container A.

Fixed to the center post 17 and adapted 100 to rotate with it are the bands 21. Reinforcing rods 22 connect the bands 21 with the center post 17.

The bands 21 are designed to receive 105 hooks 23 for supporting meat or the like.

In order to provide for introducing smoke into the container A I have provided a smudge fire box 24 which is provided with a hinged door 25 and a discharge port 26.

The hinged door 25 is provided with a 110

5 vent 27. A handle 28 pivoted to the fire box 24 is adapted when in one position to serve as a lock for holding the hinged door 25 in its closed position, as illustrated in Figures 1 and 5 of the drawings.

5 When the handle 28 is in the position shown in dotted lines in Figures 1 and 5 of the drawings it may be used for carrying the fire box from place to place.

10 The container A is provided substantially near its lower end with a pair of openings 29 which may be connected to the port 26 of the fire box 24 by means of the ordinary pipe or pipes 30.

15 The opening 29 may be interchangeably connected with the pipes 30 so that smoke from the fire box may be passed into the container from either side.

20 Closure members 31 are provided for closing the openings 29 when they are not in use.

25 When the fire box is connected with the smoke house then the opposite opening 29 may either be used as a vent opening for giving circulation to the smoke within the container, or may be closed up by the closure member 31. The openings 29 are provided with screen coverings 32, the purpose of which will hereafter be more fully described.

30 Substantially near the upper edge of the container A I have provided a discharge opening 33 which is also provided with the screen 34.

35 When it is desired smoke may be permitted to pass out of the opening 33. The closure members 31 may be interchangeably used for closing the opening 33.

40 When it is desired to have a circulation within the container and carry the smoke out, pipes 35 may be connected to the opening 33.

45 It will be understood at times that no circulation at all is required within the container, so in that case the opening 33 and one of the openings 29 are provided with the closure members 31.

50 At other times when a smoke circulation is desired one of the openings 29 is used as a vent for causing the smoke to be carried out through the opening 33.

55 After the meat has become entirely smoked and properly cured it may be left within the container A and will be safe against mice and the like, even when the openings 29 are

open, the screen 32 preventing anything from entering the container A.

55

As the meat is used the supporting rack B may be rotated for bringing any piece of meat adjacent to the door opening 14 where it may be easily removed from the rack B.

60

It will also be understood that the container A may be used for drying seed corn, since it provides a dry container and one absolutely safe against the entrance of mice or the like.

65

It will be seen that I have provided a very simple device, especially designed for use by farmers who only have a small amount of meat to cure and smoke at any one time and after the meat has been smoked, a place for storing it is provided.

70

Another advantage is the interchangeable positioning of the fire box with relation to the container A. It will be understood that the container A may be placed in the house while the fire box 24 may be placed outside 75 of the house, thus making it absolutely safe against any accidental fire.

75

Some changes may be made in the construction and arrangement of the parts of my device without departing from the real spirit and purpose of my invention, and it is my intention to cover by my claim, any modified forms of structure or use of mechanical equivalents, which may be reasonably included within its scope.

80

85 I claim as my invention:

A meat smoke house comprising a cylindrical container having a conical top and a door opening therein, a door for said opening, a vertical rotatable shaft mounted within said container, a plurality of meat supporting racks secured to said vertical shaft, a smudge fire box device for producing smoke, said fire box device having a discharge opening therein, a pair of inlet openings formed in the sides of said container, a screen covering for said inlet openings, pipes for selectively connecting one of said inlet openings with the discharge opening of the fire box, caps for closing said inlet openings, said container having an outlet opening therein, a cap for closing said last opening when desired to hold smoke in said container for all the purposes stated.
